UNITED STATES PATENT OFFICE.

WILLIAM DOWNIE, OF DETROIT, MICHIGAN.

RECEPTACLE.

1,032,472.

Specification of Letters Patent. Patented July 16, 1912.

Application filed May 27, 1911. Serial No. 629,916.

To all whom it may concern:

Be it known that I, WILLIAM DOWNIE, a citizen of the United States, and a resident of the city of Detroit, county of Wayne, and State of Michigan, have invented new and useful Improvements in Receptacles, of which the following is the specification.

My invention relates to boxes and bottles, and it has particular reference to boxes and bottles which are tightly closed to prevent the contents thereof from escaping by reason of evaporation.

When boxes are to contain a volatile substance, it is absolutely necessary that there be a very tight closure between the cover and the body of the box. It is usual to make such a box so that the cover partially telescopes over the box, or vice versa, so that there will be a considerable surface of contact between the body and the cover of the box. The surfaces of the two being tightly compressed together, it is exceedingly difficult to separate them by reason of friction, and by reason of the sticking of the surfaces, which may be due to enamel or other finishing material used for covering one of the surfaces.

In my invention I provide a means whereby the cover may be easily wedged or pried from the body of the box without in any way injuring or altering the contact surfaces, or destroying the shape of the box, and which may be as tightly closed after opening the same as before opening.

35 The invention consists, first, in providing a bead which has a good top bearing surface, thus allowing the top of the bead to act as a fulcrum. Second, in providing an outward lip on the cover, whereby a key can 40 be placed under said lip to pry up the cover, using the bead as a fulcrum. Third, in providing means to limit the position of the cover downwardly on the body of the box, and yet leave sufficient space between 45 the top of the bead and the outward lip for the key to enter. Fourth, in providing a key to open the box and also means for removably attaching the key to the box so that any time the box is to be opened the 50 key may be detached and used and then reattached to the box when the box is again

closed. In this way the key is always at hand when wanted.

The invention consists in other features described in the following description, 55 shown in the drawings and claimed in the claims.

Referring to the drawings: Figure 1, is a perspective view of the complete box, showing the key removably attached to the 60 box. Fig. 2, is a cross section of the box. Fig. 3, is a front view of a part of the box. Fig. 4, shows how the covers of the receptacle are stamped out. Fig. 5, is a special 65 style of heading. Fig. 6, is a view of the key.

Having thus described my invention in general, I will describe its details by using reference numbers, which in each of the figures refer to the same parts.

70 1, indicates the cover of the receptacle; 2, represents the body of the receptacle; 3, represents a vertical leg on three sides of the cover; 4, is a circumferential bead extending around the body of the receptacle; 75 5, is the vertical leg on each side of the lip, 6, of the cover. This lip is substantially in the same plane as the circle described by the bottom of the rim or flange.

7, is a slender extension of the lip, 6; 8, is 80 the key, having an aperture through which the strip, 7, passes, and is then bent as shown in Fig. 1; 9, is the point of the key which prays up the cover; 10, is a special form of heading; 11, is the vertical rim or the flange 85 of the cover, which tightly fits the top of the body portion.

Now it will be seen that when the box is closed, the vertical legs, 3 and 5, strike the bead, necessitating the lip, 6, of the cover 90 being a distance above the top of the bead. The key, 8, can be detached from the box by simply bending the strip, 7, then placing the point, 9, of the key under the lip, 6, and over the bead, 4, using the latter as a fulcrum, the cover can be easily pried up. When the box is again closed, the key can be placed in its proper position. Attaching the key to the box in this manner insures the purchaser of a package getting his key, 100 which otherwise a salesman might forget to give him. Also this method of retaining

the key insures the latter always being on hand when it is desired to use the material in the receptacle. If not attached to the box, it is liable to be lost. It will further be seen that no rivet holes are made in the receptacle to either dry out the contents or start a rust inside by the admission of air.

The vertical legs, 3 and 5, which are used to limit the cover downwardly on the receptacle are economical in construction, being made out of the waste corners, as shown in Fig. 4. They are better than a continuous flange all the way around the box, because the latter obscures the entire view of the bottom of flange 11; and to quickly and conveniently close a tightly fitting box, it is necessary that the entire bottom of flange, 11, be evenly placed on top of the body portion, 2, before applying pressure. This cannot be done quickly and conveniently unless the bottom of flange, 11, is pretty much in sight all the way around the box, which is the case in my construction. It will be seen that when pressure is applied to the cover forcing it down over the body portion the cover expands slightly outwardly and owing to the elasticity of the tin in the cover the latter follows minutely the circumference of the body rim in all of its multitudinous infinitesimal changes in direction. But it is evident that if a continuous flange were used all the way around the box instead of the plurality of legs, the flange 11 would be stiff being resisted in its outward expansion and consequently the contact between cover and body would not be as tight.

Different forms of beading may be used, but a style with a flat surface on top is preferable. The ordinary semi-circular bead pressed together, as shown by 10, gives a good fulcrum surface, but other styles will answer. While I prefer to increase the width of the strip, 7, into a wider lip, 6, near the flange 11, still it is not absolutely necessary, as the key can pry up the cover by engaging the narrow strip, 7, if the latter continues all the way to flange, 11. However, the construction that the drawings show of the lip, 6, is the stronger. Said lip, 6, may or may not be exactly horizontal.

Now I believe my drawings show the most economical and the best methods for making my device. Still the above mentioned variations may be made, and perhaps still others without departing from the true spirit of my invention.

What I claim as new and desire to secure by Letters Patent is as follows:

1. In a sheet metal box the combination of a cover and the body of the box, the body of the box provided with a circumferential bead, the cover provided with a flange adapted to tightly fit around the outside of the body of the box, part of said flange con-

tinuing downwardly and forming a plurality of legs which strike the bead and also part of said flange continuing outwardly and forming a lip some distance above the bead thereby forming a slot between the bead and the lip, the lip terminating in a slender extension adapted to pass through an aperture in a key and a key as heretofore described.

2. In a receptacle the combination of a body portion and a sheet metal cover, the body portion provided with a circumferential bead, the cover provided with a flange which tightly fits around the body of the receptacle, the bottom of said flange continuing outwardly and forming a lip a distance above the bead, the bottom of said flange continuing and forming also a leg on both sides of said lip and a leg at substantially the opposite extremity of the diameter of the cover of which the lip is the other extremity, said flange continuing and forming also a leg at each extremity of a diameter of the cover which is substantially perpendicular to the first named diameter, and all of the above mentioned legs extending down to the bead thereby forming a slot between the lip and the bead.

3. In a receptacle the combination of a body portion and a sheet metal cover, the body portion provided with a circumferential bead, the cover provided with a flange which tightly fits around the body of the receptacle, the bottom of said flange continuing outwardly and forming a lip a distance above the bead, the bottom of said flange continuing also and forming a leg on one side of said lip, and a leg at substantially the opposite extremity of the diameter of the cover of which the lip is the other extremity, the flange continuing also and forming a leg at each extremity of a diameter of the cover which is substantially perpendicular to the first named diameter, and all of the above mentioned legs extending down to the bead thereby forming a slot between the bead and the lip.

4. In a receptacle the combination of a body portion and a sheet metal cover, the body portion provided with a circumferential bead, the cover provided with three portions as follows, one portion being a flange which tightly fits around the body of the receptacle, a second portion being a plurality of legs which are a continuation of the above flange and extend from the bottom of the flange to the bead, abutting the latter, thereby holding the bottom of said flange a distance above the bead, said flange continuing outwardly and forming a third lip portion a distance above the bead, one of the above named three portions continuing and forming a slender extension adapted to pass through an aperture in a key and a key as heretofore described.

5. In a receptacle the combination of a body portion and a sheet metal cover, the body portion provided with a circumferential bead, the cover provided with a flange which tightly fits around the top part of the body of the receptacle, said flange continuing and forming two portions as follows, one of said portions being a lip extending outwardly a distance above the bead thereby forming a slot between the bead and said lip, a second portion being a base extending downwardly and abutting the bead thereby holding said lip a distance above the bead, the body of the receptacle 10 having portions on both sides of the lip which are free from contact with said base for the entire depth between the bead and the bottom of the above mentioned flange, one of the above mentioned two portions continuing and forming a slender extension 20 adapted to pass through an aperture in a key and a key as heretofore described.

In testimony whereof, I have signed my name to this specification, in the presence of two subscribing witnesses.

WILLIAM DOWNIE.

Correction in Letters Patent No. 1,032,472.

It is hereby certified that in Letters Patent No. 1,032,472, granted July 16, 1912, upon the application of William Downie, of Detroit, Michigan, for an improvement in "Receptacles" an error appears in the printed specification requiring correction as follows: Page 2, after line 51, insert the following paragraph: *Now in using my key and key retainer, I do not limit myself to the vertical legs to limit the position downwardly of the cover of the receptacle. Furthermore, I do not limit myself to the means employed to engage the cover and body portions of the receptacle.*; and that the said Letters Patent should be read with this correction therein that the same may conform to the record of the case in the Patent Office.

Signed and sealed this 17th day of September, A. D., 1912.
